UNITED STATES PATENT OFFICE.

WILLIAM H. CROFT AND ROBERT J. SHOEMAKER, OF CHICAGO, ILLINOIS, ASSIGNEES
TO MAGNUS COMPANY, INCORPORATED, OF NEW YORK, N. Y., A CORPORATION OF
NEW YORK.

MOLDING APPARATUS.

Application filed May 27, 1926. Serial No. 111,993.

Our invention relates to apparatus for casting metals, more particularly mixtures of metals such, for example, as copper and lead, copper, lead and tin, or other mixtures or 5 alloys used, for instance, for anti-friction bearings, bushings or the like, the ingredient metals of which tend to segregate on cooling. One of the objects of the invention is to provide certain expedients by means of which 10 this tendency to segregate will be counteracted.

A further object is to construct the elements of the mold so that the casting may be conveniently and readily removed from the mold, 15 even after the metal has set.

A further object is to provide means whereby additional metal may be supplied to the mold cavity, as shrinkage due to cooling takes place.

20 A further object is to make a casting free from molder's sand, especially objectionable if the casting has to be machined.

For castings of considerable size, it is desirable that the metals enter the mold cavity from the bottom, allowing a certain cooling of the metal and free exit of gasses to prevent porosity; and a further object of the present invention is to provide certain novel arrangements and devices for gating molds for casting operations of this sort.

The invention consists of the new and improved constructions, arrangements and devices for carrying out the above stated objects and such other incidental objects as will be 35 mentioned in the following description of the preferred embodiments of our invention illustrated in the accompanying drawing.

65

Referring first to Figs. 1 to 5 inclusive: 25 designates a metal base formed with a recess 26, and dowel holes 27. On the base and positioned by dowels 28, is an exterior mold element comprising, preferably, two semi-cylindrical members 29, formed with upper horizontal flanges 30, with lower horizontal flanges 31 and with vertical flanges 32 for the 70 fastening bolts 33 and nuts 34 by means of which the mold sections are secured together. The core or interior mold element consists preferably of three core members 35, 36 and 37, the latter having a wedging relation with 75 the other two members as indicated in Fig. 5 in which the meeting faces 38, 38 of member 37 with members 35, 36 diverge toward the central opening in the core. By this arrangement after the casting has set or partially 80 set the member 37 may be forced or driven into the central opening in the core, and removed, which will allow the removal of the other members 35, 36. Preferably the core members are formed with recesses 39 for a 85 tool used for forcing the members away from the casting. The core is intended to fit into the recess 26 in the base plate. A sand cope is provided consisting of a frame 40 of suitable material, provided with dowel holes 41 to receive the dowels 42 on flanges 30 of the exterior mold element, and a body of sand 43 formed with any suitable number of pouring and riser openings 44. These openings 90 communicate with the mold cavity 45 shown 95 in Fig. 1 as filled with the cast metal 46.

The molten metal is poured through one of the openings 44 in the sand of the cope and rises from the mold cavity into the other of said openings 44; the excess metal in these 100 openings being kept at relatively high temperature, because it is in contact with sand rather than metal, and flowing into the mold cavity to make up for shrinkage. The molten

metal in the mold cavity is in contact only with metal, the exterior and interior mold elements and the base plate being all, preferably, composed of metal, so that the molten metal in the mold cavity cools very rapidly thereby preventing segregation in the case of mixtures or alloys, the metal ingredients of which tend to segregate if cooled slowly, as happens when such metals are cast in sand molds. When the metal has been poured and set or partially set, the cope is removed, the core collapsed and the parts taken out, and the outer mold sections removed.

In Figs. 6 to 10 inclusive, a molding apparatus has been shown constructed on the same general principle as the molding apparatus just described, but with certain desirable improvements in respect, particularly, to the construction of the core, and of the ingate. The exterior mold element comprises two semi-cylindrical sections 47, 48, formed with flanges 49 for bolts 50, and with flanges 51 having dowel holes 52 to receive the dowels 53 on the base member 54. The latter is formed with a central opening 55 to receive the lower, or preferably cylindrical end 56 of a slightly tapered core consisting of core members 57, 58 and 59. The mold is shown as supported on a table or plate 60. The core members 57, 58 are in contact, substantially line contact only, at their outer surfaces. The opposed faces 61 diverge toward the central opening of the core which is annular. The meeting faces 62, 62, between the member 59 and the members 57 and 58, respectively, slope toward each other from the top of the core to the bottom, so that member 59 has a wedging relation, so to speak, with the other two core members. The cope 63 is filled with a body of sand 64 formed with any suitable number of riser openings 65, three of such openings being indicated in the drawings. The ingate is arranged on the outside of the exterior mold element and consists preferably of two members 66, 67, the latter positioned on the exterior mold section 47 by dowels 68 and the former on member 67 by dowels 69, both members being clamped to mold section 47 by any suitable means, for example, by means of the yoke 70, bolted at 71 to the mold member, and a set screw 72. Gate members 66, 67 are formed to provide an ingate duct 73 communicating with aligned diagonal ducts 74, 75, extending through gate member 67 and exterior mold section 47 into the bottom of the mold cavity 76 at a tangent thereto approximately. Preferably a pouring cup is arranged upon the gate members 66, 67, consisting of a metal cylinder 77 provided with a sand lining 78. The purpose of the sand lined pouring cup is to prevent the freezing of the metal at the top of the ingate until such time at least as the metal has subsided to compensate for shrinkage in the mold cavity. In the larger types of castings, particu-

larly, it is desirable to gate the mold to the bottom of the mold cavity for the reasons above stated.

To remove the casting from the mold the cope and pouring cup are first lifted from the exterior and interior mold elements, the gate members 66, 67 are removed and the outer mold sections unbolted and detached from the casting which is then turned upside down and the core member 59 driven out, the casting being supported over some opening or space to allow the core member 59 to be moved downwardly. The core members 57 and 58, may then be forced toward each other and removed from the opening in the middle of the casting. The casting is indicated at 79 (Fig. 10), with its sprues 80 and 81 which may be readily removed.

A somewhat different form of apparatus is shown in Figs. 11 to 15 inclusive. The exterior mold element comprises metal sections 82 flanged at 83 for the bolts 84, and provided with flanges 85 apertured for the dowel pins 86 of the base plate 87. Within the exterior mold element, with an intervening space 88 constituting the mold cavity, is an interior mold element consisting of a plurality of metal cylinder segments 89 held together by a body of molder's sand 90, portions of which 91 lie between edges of the metal members. The metal members are preferably formed with tongues 92 so as to have a better hold on the sand body, which may be either green or dried. The sand body 90 may be formed with a central pouring opening 93, communicating with ducts 94 leading through the metal members 89, at the bottom, to the mold cavity 88; or the pouring gate may be on the outside of the exterior mold element as in Figs. 6 to 10. The cope 95 is filled with a body of sand 96 provided with any suitable number of, preferably four, riser openings 97.

When the casting has cooled the exterior mold sections may be readily removed and also the core, the metal members of which will readily collapse in the dried core sand. With this construction of mold, as well as with that last described, the core may be removed from the casting with no inconvenience even after the casting has completely set, and in spite of the shrinkage of the metal on the core which necessarily occurs. In the molding apparatus of this final illustrative embodiment of my invention, the molten metal is poured through an ingate lined throughout its vertical length with sand, so that the danger of the metal freezing in the ingate is minimized. Moreover the provision of the core with the pouring duct simplifies the removal of the exterior mold sections from the casting.

While we have described our invention in certain preferred embodiments, it is the intention to cover all modifications within the scope of the appended claims,

This application is a continuation in part of our copending application Serial No. 198, filed January 2, 1925.

We claim:

- 5 1. In molding apparatus the combination of a metal base, exterior mold members secured together and mounted on said base, a plurality of separate metal core members, engageable to form a single core, and a sand 60 cope on said mold and core members.
- 10 2. In molding apparatus the combination of a metal recessed base, exterior mold members secured together and mounted on said base, a plurality of separate metal core members, 65 fitted into the recess of said base and a sand cope on said mold and core members.
- 15 3. In molding apparatus the combination of a metal base formed with a circular recess, an annular core to fit said recess comprising a 70 plurality of separate metal members divided on longitudinal lines, an annular exterior mold element comprising a plurality of metal members secured together, and supported on said base, and a sand cope arranged over said 75 mold element and core.
- 20 4. In molding apparatus the combination of a metal base, inner and outer metal mold elements, the latter formed with a duct leading to the lower part of the mold cavity, a 80 pair of gate members removably secured to the outside of the outer mold element and apertured to provide with said duct a pouring gate to the mold cavity, and a sand cope on 85 said mold element.
- 25 5. In molding apparatus the combination of a metal base, inner and outer metal mold elements, the former comprising a plurality of 90 separately removable members, the latter formed with a duct leading to the lower part of the mold cavity, and a pair of gate members 95 removably secured to the outside of the outer mold element and apertured to provide with said duct a pouring gate to the mold cavity.
- 30 6. In molding apparatus the combination of a metal base, annular inner and outer metal mold elements, the former comprising a plurality of 100 separately removable members, the latter formed with a duct leading to the lower part of the mold cavity and a pair of gate members 105 removably secured to the outside of the outer mold element and apertured to provide with said duct a pouring gate to the mold cavity.
- 35 7. In molding apparatus the combination of an outer mold element and an inner annular 110
- metal mold element divided longitudinally to provide separable members, one of which has a wedging relation with adjacent members to permit it to be removed from the finished casting, and the other members having opposed inwardly diverging faces whereby they have substantially line contact only with each other in their operative position.
- 40 8. In molding apparatus the combination of a base having an opening therethrough, an outer hollow mold element comprising separable sections on said base, an annular core arranged in the opening in the base and comprising three separable members divided on longitudinal lines, two of said members 70 formed to have line contact at their outer surfaces, and these members and the other member formed with mating faces which slope toward each other from the top to the bottom of the core.
- 45 9. In molding apparatus the combination of a base having an opening therethrough, an outer hollow mold element comprising separable sections on said base, an annular core arranged in the opening in the base and comprising three separable members divided on longitudinal lines, two of said members 75 formed to have line contact at their outer surfaces and these members and the other member formed with mating faces which slope toward each other from top to bottom of the core, and means on the outside of said outer mold element and detachably engaged therewith for providing a pouring gate leading to the bottom of the mold cavity.
- 50 10. In molding apparatus the combination of a base having an opening therethrough, an outer hollow mold element comprising separable sections on said base, an annular core arranged in the opening in the base and comprising three separable members divided on longitudinal lines, two of said members 80 formed to have line contact at their outer surfaces and these members and the other member formed with mating faces which slope toward each other from top to bottom of the core, means on the outside of said outer mold element and detachably engaged therewith for providing a pouring gate leading to the bottom of the mold cavity, and a sand lined 85 pouring cup forming the upper part of said gate.

WILLIAM H. CROFT.
ROBERT J. SHOEMAKER.
